Primary Examiner — Darlington Ly(74) *Attorney, Agent, or Firm* — JCIP Global Inc.(57) **CLAIM**

The ornamental design for a nail gun, as shown and described.

DESCRIPTION

FIG. 1 is a bottom, rear, and right side perspective view of a nail gun embodying our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken line showing of portions of the nail gun forms no part of the claimed design.
